UNITED STATES PATENT OFFICE.

GEORGE P. WASHBURN, OF LOS ANGELES, CALIFORNIA.

ACETYLENE-BURNER.

1,311,731.

Specification of Letters Patent. Patented July 29, 1919.

Application filed November 14, 1918. Serial No. 262,540.

To all whom it may concern:

Be it known that I, GEORGE P. WASHBURN, a citizen of the United States, residing at Los Angeles, in the county of Los Angeles 5 and State of California, have invented new and useful Improvements in Acetylene-Burners, of which the following is a specification.

My invention relates to an acetylene 10 burner.

An object of my invention is to provide an acetylene burner adapted for directing a pointed flame against a metal surface or joint as is done in cutting and welding 15 metal sheets and similar work.

Another object is to provide an acetylene burner which will produce a proper air and gas mixture for complete combustion and a consequent high degree of heat.

With these and other objects in view, which will appear as the description proceeds, my invention consists in the construction, combination and arrangement of parts hereinafter described and claimed.

In the accompanying drawings which form a part of this specification,

Figure 1 is a fragmentary view of an acetylene generator provided with a valve fitting to which is connected an acetylene 30 burner embodying the principles of my invention.

Fig. 2 is a central longitudinal section through the burner shown in Fig. 1 taken on the line 2-2 of Fig. 1.

Fig. 3 is an end view of the burner shown in Fig. 2 as seen looking in the direction indicated by arrow 3 in Fig. 2.

Fig. 4 is an enlarged fragmentary sectional view taken on the line 4-4 of Fig. 2 40 showing the construction of the burner nozzle.

As indicated by the reference numerals, 10 is an acetylene generator gas dome equipped with a delivery tube 11 within 45 which is a control valve operated by a handle 12. The delivery tube 11 is provided with a branch opening 13 in which a valve fitting 14 is screwed. This fitting has an acetylene outlet connection 15 to which a connecting 50 pipe 16 is joined and an air inlet connection 17 to which a compressed air pipe 18 is joined. A needle valve 19 which controls the admission of air turns in the upper part of the fitting. The burner 20 is screwed 55 into the connecting pipe 16. The burner proper consists of a circular base casting 21

with a boss 22 and a central bore 23 around which a series of equally spaced holes 24 converging from the outer to the inner part of the burner are drilled. The boss 22 has 60 an enlarged bore tapped to receive the end of a pipe 25 which connects with the connecting pipe 16.

The inner end of the central bore 23 is tapped to receive a nozzle 26, said nozzle 65 being a tube with a tapering point 27 having a central vent 28. Three or more equally spaced small holes 29 are drilled through the nozzle wall back of the tapered point at an angle of approximately 45° to the 70 nozzle axis, so that they diverge from within the tube outward.

The periphery of the base casting 21 is threaded to engage with the internally threaded end of a slightly tapering sleeve 75 30 which surrounds the nozzle and extends somewhat beyond its tapered point. An air space 31 is, therefore, left between the nozzle and the sleeve 30. A series of equally spaced holes 32 are drilled through the 80 sleeve wall around the sleeve 30 slightly forward of the base casting 21.

Operation: The burner is started with the valve operated by handle 12 closed and by opening valve 19 which will admit the air 85 which is under considerable pressure. Now a small quantity of acetylene is admitted by turning the handle 12 and the mixture is ignited at the open end of the burner 20. The quantities of acetylene and air are controlled by the handle 12 and the valve 19 respectively so that the size of the flame issuing from the open end of the burner nozzle 90 may be regulated as desired. Ordinarily the valve 19 reduces the air pressure to about 95 a quarter of a pound. The mixture of acetylene and air issues from the nozzle with considerable force and draws air through the base holes 24 and sleeve holes 32. The mixture flows out of the central opening 28 in 100 a diverging jet, it also flows through the diverging holes 29 and strikes the inner surface of the sleeve 30 at such an angle that it is reflected toward the nozzle axis beyond its point. The reflected mixture or flame 105 thus meets the diverging central jet some distance from the end of the tube and produces a pointed flame, as is indicated by the dotted lines in Fig. 4. This arrangement of a nozzle within a sleeve and the provision 110 for an adequate air supply effects a very intimate and thorough mixture of air and

acetylene, so that there is complete combustion and a consequent blue and very hot flame which when applied in the form of a converging point is very effective for use in melting metals or heating them for welding purposes.

While I have shown the preferred construction of my acetylene burner, as now known to me, it will be understood that various changes in construction, combination and arrangement of parts may be made by those skilled in the art without departing from the spirit of my invention as claimed.

I claim:

- 15 1. An acetylene burner comprising a circular base casting provided with an internally threaded central boss adapted to connect with a delivery pipe, said base casting having a central bore and a circular series of inwardly converging holes, said circular series of holes being concentric with said central bore, a nozzle fixed in said central bore, said nozzle having a tapered end which has a primary central vent and having a series of outwardly diverging secondary vents around and back of said central vent, and an enveloping sleeve attached to said base casting with its open end extending beyond said nozzle so as to deflect the gases issuing from said diverging vents 25 toward the nozzle axis, said enveloping sleeve having a series of equally spaced air inlet holes near said base casting.
- 20 2. An acetylene burner comprising a base having a central bore and a circular series of inwardly converging holes concentric with the bore; a nozzle fixed in the central bore, said nozzle having a tapered end which has a primary central vent and a series of outwardly diverging secondary vents around

and back of the central vent; and an enveloping sleeve attached to the base with its open end extending beyond the nozzle so as to deflect the gases issuing from said diverging vents toward the nozzle axis, there being air inlet openings to the chamber around 45 the nozzle and back of the point.

3. A gas burner, comprising a tubular sleeve circular in cross section, a tubular burner nozzle disposed axially therein, the outer end of said nozzle being spaced from 50 the outer end of said sleeve, the outer end of said nozzle being closed and provided with a central axial bore, said nozzle having a series of lateral radial bores outwardly inclined from the vertical, so that the flames 55 issuing therefrom will impinge points arranged in a circle on the inner side of said sleeve; means for supplying a mixture of gas and air under pressure to said nozzle; and means for supplying air to the interior 60 of said sleeve and in the rear of the outer end of said nozzle.

4. A gas burner, comprising a tubular sleeve circular in cross section, a tubular burner nozzle disposed axially therein, the 65 outer end of said nozzle being spaced from the outer end of said sleeve, the outer end of said nozzle being closed and provided with a central axial bore, said nozzle having a series of lateral radial bores outwardly 70 inclined from the vertical, so that the flames issuing therefrom will impinge points arranged in a circle on the inner side of said sleeve; and means for supplying a mixture 75 of gas and air under pressure to said nozzle.

In testimony whereof I have signed my name to this specification.

GEORGE P. WASHBURN.
